UNITED STATES PATENT OFFICE.

JOHN J. GERAGHTY, OF CHICAGO, ILLINOIS.

DESIGN FOR A MOUTHPIECE.

SPECIFICATION forming part of Design No. 31,395, dated August 15, 1899.

Application filed July 17, 1899. Serial No. 724,200. Term of patent 14 years.

To all whom it may concern:

Be it known that I, JOHN J. GERAGHTY, a citizen of the United States, residing at Chicago, in the county of Cook and State of Illinois, 5 have invented and produced a new and original Design for Mouthpieces, of which the following is a specification, reference being had to the accompanying drawings, forming part thereof.

10 My design relates to mouthpieces to be placed between the lips and teeth or gums to prevent breathing through the mouth.

15 Referring to the drawings, Figure 1 is a perspective view of a mouthpiece, showing my new design. Fig. 2 is a plan or edge view thereof, and Fig. 3 is a rear view in elevation.

As shown in the drawings, the leading or material feature of my design consists of a crescent-shaped piece or plate A, having its ends bent toward each other to form part of a 20 circle. The ends or horns a of the crescent-shaped piece are rounded, as shown.

Having described my invention, what I claim as new, and desire to secure by Letters Patent, is—

25 The design for a mouthpiece, substantially as herein shown and described.

JOHN J. GERAGHTY.

Witnesses:

CHAS. C. TILLMAN,
A. GUSTAFSON.
